PAINT STRIPING DEVICE

Charles W. Wear, Youngstown, Ohio

Application June 29, 1934, Serial No. 733,115

5 Claims. (Cl. 91—62.6)

This invention relates to paint striping devices.

The principal object of this invention is to provide a paint striping device to be used in placing ornamental stripes on an automobile body. It is understood however, that the paint striping device may be used for placing stripes on any article.

A further object of the device is to provide a pair of adjustable spring tension guide members.

A further object is to provide an adjustable guide member.

A further object is to provide a paint striping wheel mounted upon the outer end of a tubular member telescoping within a paint chamber and fitted with spring tension means.

A further object is to provide a pair of interchangeable guide members not under spring tension.

A still further object is to provide a rotatable circular band functioning on the inner end of the casing of the paint chamber, together with finger and thumb holds formed on this slideable circular band.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:

Figure 1 is a perspective view of the device with one of the spring tension guide members broken away.

Figure 2 is an enlarged section on the center of Figure 1 with the adjustable spring tension guide member removed.

Figure 3 is a perspective view of a modification of a pair of guide members to be used in place of the pair of adjustable spring tension guide members.

By referring to the drawing it will be seen that there is provided a tubular casing 1. This tubular casing 1 has both ends open. An outer end 2 of the casing 1 is provided with a tubular member 3 which telescopes within the tubular casing. It will be seen that this tubular member 3 is provided with a closed end carrying a bracket member 4 which supports a paint wheel 5. This paint wheel 5 rotates upon a pin 6 and has its perimeter extending into a paint chamber 7. It will be seen by referring to the drawings that the tubular member 3 is provided with a support member 8

which carries a rod 9, one end of which is secured to the support member 8 and the other end of which is slidably maintained within a bracket member 10. Positioned between the support member 8 and the bracket member 10 and around the rod 9 there is a compression spring 11 for the purpose of allowing the tubular member 3 and the bracket member 4 carrying the paint wheel 5 to be moved inwardly against spring compression when striping.

By referring to Figure 1 it will be seen that there is provided a yoke 12 having downwardly extended arms 13 which are adjustably supported in support brackets 14 by means of adjusting screws 15. It will be seen that this yoke 12 carries a pair of oppositely disposed adjustable spring tension guide members 16. These adjustable spring tension guide members 16 are slidably maintained within sleeves 17 which are held under tension by means of tension springs 18. One end 19 of each tension spring is secured to an end 19 of the adjustable spring tension guide members 16 while the other end is attached to the yoke 12 at a point 20. It will also be seen that there is provided an adjustable guide member 21 which is secured in the bracket member 10 by means of an adjusting screw 22. In order that the device may be caused to work efficiently there is provided a rotatable circular band 23 provided with an oppositely disposed thumb and finger hold 24.

By referring to Figure 2 it will be seen that the paint chamber 7 is provided with a piston 25 carrying a piston head 26. This piston 25 is removable in order to replenish the paint chamber 7 when necessary.

In operating the device the operator takes the device between the thumb and first finger by gripping the finger and thumb holds 24. Ball ends 27 of the adjustable spring tension guide members 16 travel upon the upper edge of a bead 40 ordinarily formed on automobile bodies. A lower ball end 28 formed on the adjustable guide member 21 slides along the surface of the automobile body. It will be readily seen that the position of the striping may be varied in relation to the bead by raising or lowering the downwardly extending arms 13 in the brackets 14.

It is also pointed out that the adjustable spring tension guide members allow for a flexibility in the operation of the device and together with the compression spring 11 controlling the tension of the paint wheel 5, provides for a constant and desirable pressure on the paint wheel 5. While these adjustable spring tension guide members allow for flexibility in the operation of the device,

the single adjustable guide member establishes a firm contact with the object being striped.

It will also be understood that one of the difficulties in manipulating stripers is to paint around turns or curves. This may be done easily and accurately with this device by means of the rotatable circular band 23 giving freedom sufficient to allow the adjustable spring tension guide members 16 to follow the bead without unnecessary twisting of the operator's wrist or fingers.

By referring to Figure 3 it will be seen that there is provided a modification 29 of the yoke 12 with downwardly extending arms 30. It will be seen that in place of the adjustable spring tension guide members 16 there is provided a pair of oppositely disposed guides 31 with off-set ends 32. This modified yoke 29 is used where the operator is following an edge such as louvres on the hood of an automobile. In that case the off-set ends 32 slide along the edge of the louvres.

What I claim is:—

1. In a device of the class described, a tubular casing, a tubular member telescoping within an end of said tubular casing, one end of said tubular member being closed, a bracket and paint wheel carried in said closed end of said tubular member, spring compression means mounted upon said tubular member for controlling the telescoping of the tubular member within the tubular casing when pressure is exerted upon said paint wheel, a plurality of adjustable guide members adjustably mounted in said tubular casing.

2. In a device of the class described, a tubular casing, a tubular member telescoping within an end of said tubular casing, the outer end of said tubular member being closed, a bracket and paint wheel carried in said closed end of said tubular member, spring compression means mounted upon said tubular member for controlling the telescoping of the tubular member within the tubular casing when pressure is exerted upon said paint wheel, a plurality of spring tension guide members adjustably mounted on said tubular casing, a single adjustable guide member mounted on said tubular casing for the purpose of forming a firm contact with the object being painted.

3. In a device of the class described, a tubular casing, a tubular member telescoping within an end of said tubular casing, the outer end of said tubular member being closed, a bracket and

paint wheel carried in said closed end of said tubular member, spring compression means mounted upon said tubular member for controlling the telescoping of the tubular member within the tubular casing when pressure is exerted upon said paint wheel, a plurality of spring tension guide members adjustably mounted on said tubular casing, a single adjustable guide member mounted on said tubular casing for the purpose of forming a firm contact with the object being painted, a rotatable circular band positioned on one end of said tubular casing, oppositely disposed thumb and finger holds on said rotatable circular band. 5 10

4. In a device of the class described, a tubular casing, a tubular member telescoping within an end of said tubular casing, the outer end of said tubular member being closed, a bracket and paint wheel carried in said closed end of said tubular member, spring compression means mounted upon said tubular member for controlling the telescoping of the tubular member within the tubular casing when pressure is exerted upon said paint wheel, a plurality of guide members mounted on said tubular casing, an off-set end on each of said guide members, a rotatable circular band positioned on one end of said tubular casing, oppositely disposed thumb and finger holds on said rotatable circular band. 15 20

5. In a device of the class described, a tubular casing, a tubular member telescoping within an end of said tubular casing, one end of said tubular member being closed, a bracket and paint wheel carried in said closed end of said tubular member, spring compression means mounted upon said tubular member for controlling the telescoping of the tubular member within the tubular casing when pressure is exerted upon said paint wheel, support brackets mounted on said tubular casing, a yoke, downwardly extended arms on said yoke, said yoke and downwardly extended arms adjustably supported within said brackets, oppositely disposed sleeves carried in said yoke, a plurality of adjustable spring tension guide members carried in said sleeves, a bracket member formed on said tubular casing, 35 40 45 a single adjustable guide member secured within said bracket member, a rotatable circular band positioned on one end of said tubular casing, oppositely disposed thumb and finger holds on said rotatable circular band. 50

CHARLES W. WEAR.
